UNITED STATES PATENT OFFICE.

LEWIS WILLIAM HARDING, OF NORFOLK, VIRGINIA, ASSIGNOR OF ONE-HALF TO
JOHN A. LESNER.

SAFETY-FLAP POCKET REGISTRY-ENVELOP.

1,393,776.

Specification of Letters Patent.

Patented Oct. 18, 1921.

Application filed October 18, 1919. Serial No. 331,583.

To all whom it may concern:

Be it known that I, LEWIS W. HARDING, a citizen of the United States, residing at Norfolk, in the county of Norfolk and State of Virginia, have invented certain new and useful Improvements in Safety-Flap Pocket Registry-Envelops; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to envelops, and is designed primarily to form an envelop for transmission of valuables, for instance by registered mail or otherwise, and which will afford additional security against rifling, and which is also adapted for attachment of a registry return card without liability of its accidental detachment in transmission of the envelop or package to its destination point. The invention contemplates forming the envelop with what for convenience I will designate as a safety flap which effects such a sealing of the envelop that it cannot be surreptitiously opened without affording quickly identifying evidence of the unauthorized tampering with the sealed container or envelop. It is also formed with a pocket for receiving and securely holding a return receipt card, the pocket being so formed as to be reinforced at points where the greatest strain and liability to fracture occur.

To the accomplishment of the foregoing and such other objects as may hereinafter appear the invention consists in the features hereinafter particularly described and then sought to be clearly defined by the claims, reference being had to the accompanying drawings forming a part hereof, and in which—

Figure 1 is a perspective view of an envelop in which is embodied the invention, a registry return card being shown in place, and the sealing flaps at one end being partially turned back for clearness of illustration;

Fig. 2 is a view similar to Fig. 1 with the main flap and one of the preferred form of end sealing flaps in opened positions for clearness of illustration;

Fig. 3 is a perspective view of an embodi-

ment of the invention with parts opened up or turned out for clearness of illustration;

Fig. 4 is a perspective view of one form of blank employed in making the envelop;

Fig. 5 is a vertical section on the line *a—a* 60 of Fig. 2;

Fig. 6 is a vertical section on the line *b—b* of Fig. 2;

Fig. 7 is a horizontal section on the line *c—c* of Fig. 2;

Fig. 8 is a horizontal section on the line *d—d* of Fig. 3;

Fig. 9 is a perspective view similar to Fig. 2, showing a modification, with parts unfolded for clearness;

Fig. 10 is a vertical section on line *e—e* of Fig. 9;

Fig. 11 is a longitudinal section on line *f—f* of Fig. 9.

In the drawing the numeral 1 indicates 75 the main body of the envelop or blank which is formed with end flaps 2, bottom flap 3 and top flap 4. Each end flap is formed with a central portion 5 which will fold along the creases 6 and 7 so as to bring the portion 80 5 overlapping the adjacent portion 8 and be cemented along the inner face of the portion 9 so that when the portion 9 is folded inwardly along the crease 11 a reinforced open sided receiving pocket 10 will be formed at 85 the outer face of the inwardly folded end portions 8 of the two end flaps, the open ended pockets being opposite each other, and the inwardly folded portions 8 at their meeting edges being cemented one to the other 90 to form the front of the envelop. The upper ends of the portions 5 are slotted and cut so as to form a lip 12 that will be cemented to the inner face of the portion 9, and a lip 13 that will be cemented to the outer face of the 95 portion 8 so as to secure the upper part of the portions 8 and 9 together at the rear of the pocket, and the portions 8 and 9 together at the top of the pocket. At the lower ends of the portions 9 the blank will be formed with inwardly extending lips 14 which will be cemented to the inner face of the bottom flap 3 when folded up on to the inturned end flaps, and to each side of the bottom flap 3 flaps 15 are formed which will be folded or 100 upturned so as to overlap the portions 9 at the bottom and thus close the bottom of the envelop at the ends. The bottom flap 3 is formed with curved edges which form lips 16 at the ends of the bottom flap which 105

110

will fit within or enter the pockets and be cemented to the faces of the inturned portions 8 of the end flaps so as to effect an attachment or connection between the end flaps 5 and bottom flap without affecting the opening of the pockets, and at the same time concealing the ends of the bottom flap. The top flap 4 is cut away at 17 so as to form end lips 18 and end flaps 19, the lips 18 being 10 designed to fit under or within the pockets and the flaps 19 to fold into the portions 9, when the top flap is folded for closing and sealing the envelop, the inner faces of the lips 18 and flaps 19 being cemented or 15 gummed for sealing purposes.

The lower flap 3 is provided with an auxiliary or safety flap designed to fold over the top flap 4 when the latter is in sealing position and to be sealed thereon so as to afford 20 safety against surreptitious opening of the top sealing flap without tangible or optical evidence of tampering. This safety flap is designated by the numeral 20 and may be formed in different ways. In Fig. 2 of the 25 drawing it is illustrated as formed along the top edge of the bottom flap 3. Its inner face is gummed and normally will be folded outward so that when the top flap 4 is in sealing position, the safety flap will be turned 30 down upon the top flap and sealed thereto, with the ends of the safety flap lying under or within the return card pockets.

An envelop formed with the return receipt 35 pockets and with the safety flap possesses material advantages. The pockets admit of the easy insertion of the return receipt card, designated by 21, and securely retain the same against accidental displacement or detachment during transmission by mail, or 40 otherwise. The pockets are also reinforced by the manner in which they are formed so that they afford strength where the strains occur, and they also prevent the insertion of any instrument for extracting contents of 45 the envelop. The safety flap covers and conceals the seal of the main flap and thereby prevents the unlawful unsealing and opening of the sealing flap so that additional security is afforded. The other features described also give greater security and protection and strength to the envelop.

Modifications can be made in the inventive 55 features of the envelop and their advantages secured. For instance, instead of having the end flaps made separate from each other and their adjacent ends joined by a seam a single flap may be extended from one end to the other and have its end cemented to the flap 8 under the central pocket portion 5, as 60 indicated in Fig. 8 of the drawing. This is practically a lengthening or prolongation of one end flap and a shortening of the other, the two being cemented together at their meeting points but the seam being concealed 65 instead of being exposed as when the two

ends meet at the middle portion of the envelop.

In another modification, both end flaps may be shortened so that the portions 8 thereof, instead of meeting at the middle of 70 the envelop, or one being prolonged so as to meet the other shortened end flap, may each terminate adjacent to the pockets of the envelop, and the bottom flap 3 may be continued all the way to the top and cemented 75 at its ends to the shortened portions 8 of the end flaps, as shown in Fig. 9 of the drawing. In the several forms described the inventive features are substantially the same, the only difference between them being in form and 80 not in substance.

So also, the safety flap 20 instead of being a single thickness may be a double thickness and made by folding the bottom flap between its lower and upper ends with the 85 meeting faces of the fold cemented together, and the inner face of the flap gummed so that when folded down over the top flap when in sealing position it will cover and conceal the seal of the top flap as in the 90 other form described.

This form of safety flap is illustrated in Fig. 9 of the drawing.

If desired, the lower or bottom auxiliary flaps 15 instead of terminating near the bottom of the envelop may be extended as far as the upper part of the envelop and formed with gummed tabs 22 which when the top flap is turned down into sealing position, these tabs may fold over the sealing flap, at 100 opposite ends of the envelop, as illustrated in Figs. 1 and 2 and thus serve as supplemental seals to the envelop.

I have described and illustrated some of the modifications that may be made but I am 105 not restricted to such modifications as others may be made and be embraced within the novel features described and illustrated in their preferred form.

Having described my invention and set 110 forth its merits, what I claim is:

1. An envelop provided with inwardly extending end flaps, each flap folded upon itself to form an externally located pocket to receive a return card, and means connecting 115 one flap with the other.

2. An envelop provided with inwardly extending end flaps, each flap folded upon itself to form an externally located pocket to receive a return card, one face of the folded 120 pocket portion being cemented to the adjacent inturned flap portion.

3. An envelop provided with inwardly extending end flaps and oppositely disposed externally located pockets to receive a return card, and an upwardly extending bottom flap having lips at its edges to fit within 125 said pockets.

4. An envelop provided with inwardly extending end flaps and oppositely disposed 130

- 5 pockets to receive a return card, an upwardly extending bottom flap having end portions secured to the inwardly extending end flaps beneath said pockets, and supplemental bottom flaps folded upon and secured to the inwardly turned end flaps at the ends of the envelop.
- 10 5. An envelop provided with inwardly extending end flaps and oppositely disposed pockets to receive a return card, and a top sealing flap having end portions to fit under said pockets.
- 15 6. An envelop provided with inwardly extending end flaps and oppositely disposed pockets to receive a return card, a top sealing flap having end portions to fit under said pockets, and supplemental top flaps to be folded upon and secured to the inwardly turned end flaps at the ends of the envelop.
- 20 7. An envelop provided with inwardly extending end flaps and oppositely disposed pockets to receive a return card, an upwardly extending bottom flap and supplemental bottom flaps folded upon and secured to the inwardly turned end flaps at the ends of the envelop,
- 25 to the inwardly turned end flaps, a top sealing flap having end portions to fit under said pockets and supplemental flaps to be folded upon and secured to the inwardly turned end flaps at the ends of the envelop,
- 30 and supplemental sealing tabs arranged to

overlap and be secured to said supplemental flaps.

8. An envelop provided with inwardly extending end flaps and oppositely disposed pockets to receive a return card, a top sealing flap having end portions to fit under said pockets, and a safety flap disposed to overlap the lower edge of said downwardly turned top flap.

9. An envelop provided with inwardly extending end flaps and oppositely disposed pockets to receive a return card, a top sealing flap, and an upwardly extending bottom flap projecting beneath said top flap and folded between its top and bottom to form a safety flap disposed to overlap the lower edge of the downwardly turned top flap.

10. An envelop provided with inwardly extending end flaps, a downwardly foldable top sealing flap, an upwardly extending bottom flap, and a safety flap attached to the bottom flap and disposed to overlap and conceal the lower edge of the downturned upper flap and be sealed thereto.

In testimony whereof I affix my signature in presence of two witnesses.

LEWIS WILLIAM HARDING.
